ATTORNEY

UNITED STATES PATENT OFFICE.

GEORGE BLACKBURN, OF COLUMBUS, OHIO, ASSIGNOR TO THE STANDARD BOILER AND SMOKE CONSUMING FURNACE COMPANY, OF SAME PLACE.

SMOKE-CONSUMING FURNACE.

SPECIFICATION forming part of Letters Patent No. 277,978, dated May 22, 1883.

Application filed November 28, 1882. (No model.)

To all whom it may concern:

Be it known that I, GEORGE BLACKBURN, of Columbus, Franklin county, Ohio, have invented certain new and useful Improvements 5 in Smoke-Consuming Devices, of which the following is a specification.

This invention pertains to smoke-consuming devices for application to furnaces used in connection with steam-engines; and it consists of 10 an arrangement of pipes for conveying the exhaust-steam from the steam-engine through a superheater to the furnace, and of a peculiar arrangement of the furnace-walls, all as hereinafter set forth.

15 In the accompanying drawings, Figure 1 is a vertical longitudinal section of a boiler-furnace embodying my improvements; and Fig. 2 is a vertical transverse section of the same.

In the drawings, A represents the boiler; 20 B, the boiler-flues; C, the breeching; D, the smoke-stack; E, the ash-pit; F, the grate; G, the fire-place; H, the bridge-wall; I, the fire-door; J, the ash-pit door; K, the tail-wall; L, the flue-plate; M, the tail-wall door; S, the 25 steam-engine; and T, the engine's exhaust-pipe, all constructed and arranged substantially as usual.

N is a wall under the tail end of the boiler; O, a flue or opening through the base of wall 30 N; P, a wall under tail of boiler, near wall N; Q, a flue or space between the top of wall P and the bottom of the boiler; R, a superheating-pipe built in the top of the bridge-wall; U, a pipe from exhaust-pipe T to the superheater 35 R; V, pipes from superheater R to front of fire-place G, above the fire; W, jet-holes in front ends of pipes V, issuing over the fire; and X, a valve in exhaust-pipe T, above the point where pipe U connects with the exhaust- 40 pipe T.

In operation the valve X is slightly closed,

so as to produce a slight reactive pressure in the exhaust-pipe. This slight pressure, reacting on the steam-pressure, will produce no serious damaging effect on the engine-power. 45 By reason of this slight pressure part of the exhaust-steam passes to the superheater, where it becomes superheated, or at least has its temperature somewhat raised. The steam leaves the superheater by the pipes V, and jets out 50 over the fire in front and joins the products of combustion. The mingled gases pass over the bridge-wall and impinge against the current-breaking wall P and become retained a time in the chamber in front of that wall, the 55 current, much contracted in area of stream, continuing through space Q over said wall, thence under wall N, thence out, as usual. The wall N tends to protect the tail of the boiler from the impingement of the hot gases on 60 their turn upward to the boiler-flues. The steam-pipes are best when built within the brick-work to protect them from burning; but they may be exposed direct to the action of the fire or hot gases, and the location of the pipes 65 may be changed without departing from the spirit of the invention.

I claim as my invention—

1. The combination of engine S, exhaust-pipe T, valve X, boiler A, furnace G, superheater R, jettied pipes V, pipe U, bridge-wall H, walls P, N, and K, and flues or openings Q and O, substantially as set forth.

2. The combination, in a boiler-furnace, of wall P, having opening Q, and wall N, having 75 openings O and c and doors d, substantially as set forth.

GEO. BLACKBURN.
